Primary Examiner—Louis S. Zarfas*Assistant Examiner*—Catherine R. Oliver*Attorney, Agent, or Firm*—Bielen, Peterson & Lampe[57] **CLAIM**

The ornamental design for an combined armband holster and ammunition pouch, as shown and described.

DESCRIPTION

FIG. 1 is a perspective view showing my new design of an combined holster and ammunition pouch as viewed from the back of a wearer when the unit is worn;

FIG. 2 is a front elevational view thereof;

FIG. 3 is a bottom view thereof;

FIG. 4 is a rear view thereof;

FIG. 5 is a top view thereof;

FIG. 6 is a right side view of the holster portion of the unit thereof;

FIG. 7 is a left side view of the holster portion of the unit thereof;

FIG. 8 is a right side view of the ammunition pouch portion of the unit thereof; and,

FIG. 9 is a left side view of the ammunition pouch portion of the unit thereof.

The broken line showing of environment in the drawings is for illustrative purposes only and forms no part of the claimed design.
